UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DOOR-OPERATING MECHANISM FOR CARS AND THE LIKE.

1,256,771.

Specification of Letters Patent. Patented Feb. 19, 1918.

Application filed August 20, 1917. Serial No. 187,125.

To all whom it may concern:

Be it known that I, ARGYLE CAMPBELL, a citizen of the United States, residing at Chicago, in the county of Cook and State of Illinois, have invented a certain new and useful Improvement in Door-Operating Mechanism for Cars and the like, of which the following is a full, clear, concise, and exact description, reference being had to the accompanying drawings, forming a part of this specification.

This invention relates to improvements in door operating mechanism for cars and the like.

15 The object of my invention is to provide a mechanism for operating so-called twin hopper doors of hopper cars and similar constructions, the mechanism being so arranged that, when the doors are in closed position, the mechanism is self-locked to prevent accidental opening of the doors when the load is applied thereon and more especially, the invention contemplates a mechanism of the type above indicated 20 which is composed of a minimum number of parts to thereby decrease cost, prevent possibility of getting out of order and insure greater certainty in the self-locking feature.

In the drawing forming a part of this 30 specification, Figure 1 is a side elevation of a portion of a hopper car of a type to which my improvements are especially adapted, there being two hoppers of the car shown. Fig. 2 is a top plan view taken on a level 35 with the tops of the center sills of the car and illustrating more particularly the improved door locking mechanism. Fig. 3 is a vertical, sectional view taken substantially on the line 3—3 of Fig. 2 and showing the 40 position occupied by the parts when the doors are in closed position. Fig. 4 is a vertical, transverse, sectional view corresponding substantially to the section line 4—4 of Fig. 3. And Fig. 5 is a view corresponding to Fig. 3, but illustrating the position of the parts when the doors are in 45 open position.

In said drawing, the car is designated generally by the reference A and is of that 50 type having four sets of hoppers between the trucks on each side of the center sill. Fig. 1 illustrates that portion of the car between one of the trucks and the transverse center of the car. The car is provided with 55 the usual center sill construction comprising

a pair of outwardly turned channels 10—10, as most clearly shown in Figs. 2 and 4. Each hopper, on each side of the center sill, is provided with twin hopper doors 11—11, the same being pivotally supported as indicated at 12—12 and the doors being adapted to have their free edges meet when the doors are in closed position. Each pair of doors 11 which are in transverse alinement are connected by a transversely extending U- 60 shaped cross bar 13 so that all the doors for each pair of transversely alined hoppers are operated simultaneously.

The operating mechanism which I have designed is arranged as follows: Secured to 70 the inner faces of the channel center sills 10—10 are bearing brackets 14—14 which support a short shaft 15. Mounted on the shaft 15, which is of non-circular cross section intermediate its ends, are two sheave-wheels 16—16 and a drum or hub 17 interposed therebetween. As will be understood, the sheave-wheels 16 and drum 17 fit the shaft 15 so as to move in unison therewith. The drum 17, when the doors are in closed 80 position, as illustrated in Fig. 3, is provided with a forked lever arm 18 which extends downwardly and has pivotally connected thereto, as indicated at 19, a link 20 which has an angular or hook-shaped end 21. The 85 link 20 is preferably made from two similarly shaped elements 120—120 held in spaced relation between the forks of the arm 18, as most clearly appears from Fig. 3. The link 20, when the doors are in closed 90 position, extends upwardly and is inclined from the vertical toward the center line of the shaft 15, as appears from Fig. 3, and the hook-shaped end 21 thereof is supported on a ledge or shelf portion 22 of the hub 17. 95 The elements 120 of the link 20 rest against correspondingly disposed shoulders 123 on the hub 17.

From the cross bar 13 connecting one pair of doors 11, extends an adjustable eye-bolt 100 24 to which is pivotally connected a hook-shaped link 25 formed of two like elements 125—125 fitted over the two elements 120—120. The hook-shaped end 26 of said link 25 is pivotally connected to the link 20, 105 as by a rivet 27, at a point substantially at the angle between the main portion of the link 20 and its hook-shaped end 21, as will appear from an inspection of Fig. 5. To the other cross bar 13 connecting the op- 110

posed set of doors 11 is adjustably attached an eye-bolt 28, the bolt 28 having pivotally connected thereto a third hook-shaped link 29. The link 29 has the hook portion thereof 30 pivotally connected to the end of the extension 21 of the link 20, as indicated at 31, and which is most clearly shown in Fig. 5. The link 29 is preferably made forked below the line 32 so that the forked portions of said link are adapted to straddle the eye-bolt 28 and be pivotally connected thereto. At its upper end, the link 29 is fitted between the elements 120—120 and pivoted thereto as by the countersunk rivet indicated at 31. When the doors are in closed position, the hook-shaped portion 26 of the link 25 is adapted to rest also on said ledge or bearing portion 22 of the hub 17 and the hook-shaped portion 30 of the forks of the link 29 rest upon a ledge 122 of the hub 17 and both links 25 and 29 are adapted to bear against the hub 17 on the left hand side thereof, as viewed in Fig. 3.

From the sheave-wheels 16—16 extend chains 34 and 35, said chains running over other sheave-wheels 36—36 mounted on a transversely extending shaft 37. The shaft 37 is extended to the side of the car and is provided on the end thereof with a squared section 38 by which it can be operated with a claw bar or other suitable instrument. To lock the shaft 38 against accidental rotation, it is provided with a ratchet wheel 39 in the usual manner with which co-operates a pawl 40, the pawl being locked by a dog 41.

By referring to Fig. 3, it will be seen that the line B—B which extends between the pivotal connection 27 and the point of 40 pivotal connection between the link 25 and its door 11 is located to the right hand side of the center of the shaft 15. Similarly, the line C—C which extends between the pivotal connection 31 and the connection be- 45 tween the link 29 and its corresponding door 11 is also located to the right hand side of the center of the shaft 15. Consequently, when the doors are in closed position, as shown in Fig. 3, there will be no tendency 50 for the load on the doors 11 to rotate the shaft 15 in an unwinding or counter-clockwise direction. In other words, all load on the doors will be transferred to the shaft 15 without exerting any turning or torsional 55 effect thereon. With this construction, both of the twin doors of each set are independently locked with respect to the shaft so as to prevent unwinding of the door operating mechanism. Furthermore, it will be noted 60 that there are only three links interposed between the hub and the twin hopper doors, an absolute minimum number of parts. This reduces the cost of material, simplifies the construction and minimizes danger of the 65 parts becoming distorted or broken during

operation. As will be understood, the shaft 37 when rotated in one direction will operate one chain to rotate the shaft 15 in a clockwise direction and vice versa through the other chain to rotate the shaft 15 in a counter-clockwise direction.

Although I have herein shown and described what I now consider the preferred manner of carrying out my invention, the same is merely illustrative and I contemplate 75 all changes and modifications that come within the scope of the claims appended hereto.

I claim:

1. In door operating mechanism for a 80 hopper car or the like having twin arranged pivoted doors, the combination with a shaft located above the doors, of a hub on said shaft, a link pivotally connected at one end to said hub and at its opposite end provided 85 with an angular extension, a hanger link pivotally connected at one end to said angular extension and at its opposite end to one of said doors, and a second hanger link also pivotally connected at one end to said first 90 named link and at its opposite end to the other door.

2. In door operating mechanism for a 95 hopper car or the like having twin arranged pivoted doors, the combination with a shaft located above the doors, of a hub on said shaft, a link pivotally connected at one end to said hub and at its opposite end provided with an angular extension, a hanger link pivotally connected at one end to said angular extension and at its opposite end to one 100 of said doors, and a second hanger link also pivotally connected at one end to said first named link and at its opposite end to the other door, said hanger links, when the doors 105 are in closed position, being supported from said hub and having the lines located by the pivotal connections between each hanger link and its corresponding door and the connections between each hanger link and the 110 first named link beyond the center of the shaft.

3. In door operating mechanism for a 115 hopper car or the like having twin arranged pivoted doors, the combination with a shaft, of a hub mounted on said shaft, and three links each having a hook-shaped end, one of said links being pivotally connected at its plain end to the hub, each of the other two links being also pivotally connected at its 120 plain end to a door and said two last named links having their hook-shaped ends pivotally connected to the hook-shaped end of the link pivotally connected to the hub.

4. In door operating mechanism for a 125 hopper car or the like having twin arranged pivoted doors, the combination with a shaft, of a hub mounted on said shaft, and three links each having a hook-shaped end, one of said links being pivotally connected at its 130

- plain end to the hub, each of the other two links being also pivotally connected at its plain end to a door and said two last named links having their hook-shaped ends pivotally connected to the hook-shaped end of the link pivotally connected to the hub, the hook-shaped ends of all three links being supported on the top of the hub when the doors are in closed position.
- 5 5. In a hopper car, the combination with a pair of pivotally mounted hopper doors adapted to have their free edges meet when the doors are in closed position, of a shaft disposed above the meeting edges of the
- 10 doors, a hub mounted on said shaft, a hook-shaped link pivotally attached at one end to said hub, a hook-shaped link pivotally connected at one end to one of said doors and at its opposite end to the end of said
- 15 first named link, and a third hook-shaped link pivotally connected at one end to the other of said doors and at its opposite end to the first named link at a point removed from the end thereof, the pivotal connections between various parts being so ar-
- 20
- 25

ranged that, when the doors are in closed position, the load will exert no tendency to rotate said shaft in an unwinding direction.

6. In door operating mechanism for a hopper car and the like having twin arranged pivoted doors, the combination with a shaft, of a hub mounted on said shaft, a link pivotally connected to said hub, said link comprising a pair of spaced elements hook-shaped at one end, a hook-shaped link 30 pivotally connected at one end to one of said doors and pivotally connected at its opposite end to the first named link and fitting between the elements comprising the latter, of a third link pivotally connected at one 35 end to the other of said doors, said third link being formed of two spaced elements straddling the second named link and pivotally connected at its opposite end to the outer sides of the two elements forming the 40 first named link.

In witness that I claim the foregoing I have hereunto subscribed my name this 8 day of Aug. 1917.

ARGYLE CAMPBELL.
